UNITED STATES PATENT OFFICE

CLARK SEALEY, OF VERMILION, SOUTH DAKOTA

CLOSURE FASTENER FOR RECEPTACLES

Application filed October 16, 1929. Serial No. 400,092.

This invention appertains to new and useful improvements in closures particularly adapted for closing egg cases, and the principal object of the invention is to provide a closure or lid adapted for detachable disposition on an egg case so that it may be easily removed and preserved for re-use.

Another important object of the invention is to provide a closure for egg cases which 10 may be easily adjusted to position on an egg case and secure thereto without difficulty.

Another important object of the invention is to provide an egg case closure which will allow a reasonably wide range for adjustment.

These and various other important objects and advantages of the invention will become more apparent to the reader after considering the invention as described and claimed 20 hereinafter.

In the drawings:

Figure 1 represents a bottom plan view of the novel lid.

Figure 2 represents a top plan view of the 25 novel lid structure.

Figure 3 represents a top plan view of the lid with the fastening means in operated position.

Figure 4 represents an end elevation of 30 the box with the lid applied.

Figure 5 represents a side elevation of an egg case with the novel lid structure secured thereon.

Figure 6 represents a cross sectional view 35 taken substantially on line 6-6 of Figure 3.

Figure 7 represents a cross sectional view taken substantially on line 7-7 of Figure 3.

Figure 8 represents a cross sectional view taken substantially on line 8-8 of Figure 3.

Figure 9 represents a fragmentary sectional view taken substantially on line 9-9 of Figure 3.

Figure 10 represents a perspective view of the abutment plate.

Figure 11 represents a perspective view of one of the movable latch bars.

Figure 12 represents a perspective view of one of the stationary latch bars.

Figure 13 represents a perspective view of 50 one of the securing arms.

Figure 14 represents a perspective view of the complementary securing arm.

Figure 15 represents a perspective view of the bolt.

Referring to the drawings, wherein like 55 numerals designate like parts, it will be seen that the detachable and re-usable lid is to be employed upon an egg case of the type disclosed in the drawings. This type of egg case includes the side walls 5 and end walls 60 6 and to these end walls at their upper edges are secured the horizontally disposed cleats 7.

The novel lid or closure includes a rectangular shaped plate or board 8, which may be of metal or wood, without departing 65 from the spirit and scope of this invention. Snugly surrounding the board 8 and adjacent each end thereof is a strap 9, secured to the board in the manner shown clearly in Figure 8, and secured thereto by bolts and 70 nuts 10 and 11 respectively.

Disposed transversely upon the board 8 and at the intermediary thereof is an abutment plate 12 which is provided with a short upstanding flange 13 at an intermediate point on one longitudinal edge. A pair of stationary latch bars 14-14 each has one of its ends secured to one end of the abutment plate 12 (see Figure 3) while its opposite end is bent downwardly as at 15 and inwardly as at 16 to provide a hook for engagement over the cleat 7 at one end of the egg case.

Connecting the stationary latch bars 14-14 adjacent their hooked ends is a bar 85 17 for maintaining the said latch bars properly spaced apart. These bars 14-14 are also secured to the straps 9 as at 18.

Also disposed longitudinally on the board 8 are the movable latch bars 19-19. One 90 of these latch bars 19 is pivotally connected to the securing arm 20 as at 21 and this securing arm 20 is pivotally connected to the abutment plate 12 at one end as at 22. The opposite end of this particular latch bar 19 is provided with a laterally disposed portion 23 and an inwardly disposed extremity 24 to provide a hook for engagement over the cleat 7 at the opposite end of the case.

The other latch bar 19 is pivotally con- 100

nected at its inner end as at 25 to the securing arm 26 and this securing arm 26 is pivotally connected at one end to one end of the abutment plate 12 as at 27.

5 The free end of the arm 20 is provided with a rectangularly shaped loop 28, and a second and somewhat narrower loop 29 inwardly on the same arm, this construction being clearly shown in Figure 13. The arm 10 26 is provided with a single loop 30 at its free end and the loops 28 and 30 can be moved against the flange 13 of the abutment plate 12 in the manner shown in Figure 3 and when the securing arms are in this position (aligned) the latch bars 19-19 are in re-15 tracted positions so as to engage the hooks at their free ends over the cleat 7 at that particular end of the egg case.

To prevent displacement of the latch bars 20 19-19, upstanding pins are provided on the corresponding strap 9 and project through the obliquely disposed slots 31 in the said latch bars.

In order to secure the arms 20 and 26 in 25 aligned relation, a bolt 32 is slidably disposed on the arm 20 so as to project through the loops 28 and 29. By projecting the bolt 32 toward the arm 26, the bolt may be engaged through the loop 30 on the arm 26, so that 30 these arms are secured together, thus fastening the latch bars 19-19 so that the lid 8 will remain snugly on the egg case.

The bolt 32 is bifurcated as at 33 and the portion between the furcations thereof is bent 35 upwardly to provide a stop 34 engageable with the loop 29.

While the foregoing specification sets forth the invention in detail, it is to be understood that numerous changes in the shape, 40 size and materials may be resorted to without departing from the spirit and scope of the invention as claimed hereinafter.

Having thus described the invention, what is claimed as new is:

45 A fastener comprising a plate, a stationary hook member projecting from the plate, a pair of bars, each of said bars being provided with a hook at one end, a pair of pivotal levers on the plate, one end of each lever being secured to the end of one of the bars opposite from its hooked end, a slip connection 50 between the remaining ends of the levers whereby said levers can be secured against movement.

55 In testimony whereof I affix my signature.

CLARK SEALEY.
